UNITED STATES PATENT OFFICE.

HENRY H. NEWBY, OF SAN QUENTIN, CALIFORNIA.

SURF-BOARD.

1,324,687.

Specification of Letters Patent.

Patented Dec. 9, 1919.

Application filed December 14, 1917, Serial No. 207,131. Renewed May 10, 1919. Serial No. 296,056.

To all whom it may concern:

Be it known that I, HENRY H. NEWBY, a citizen of the United States, residing at San Quentin, in the county of Marin and State 5 of California, have invented new and useful Improvements in Surf-Boards, of which the following is a specification.

This invention relates to a surf board which is in the nature of a catamaran 10 through the use of which the pleasure derived from surf boating and bathing may not only be materially increased but such boating and bathing rendered safe to inexperienced persons.

15 The primary object of the invention is to provide an inexpensive device of this character wherein provision is not only made for permitting the person using the device to propel himself over the surface of the 20 water, but to so construct the device that the person lying thereon may freely use his feet and legs for controlling the direction of travel of the board.

Another object of the invention is to provide 25 the board with a propeller which has associated therewith mechanism of novel construction through the operation of which the propeller may be set in motion to cause the board to travel over the surface of the 30 water.

A further object of the invention is to provide a device of this character wherein a plurality of floats are attached to a board which is recessed upon opposite sides adjacent 35 one end of the board in such a manner that a person lying thereon may have free use of his or her feet and legs for the steering of the board over the surface of the water.

40 A further object of the invention is to provide hangers of novel construction for the propeller operating mechanism associated therewith.

With these and other objects in view, the 45 invention resides in the novel combination and arrangement of parts, which will be hereinafter described and particularly pointed out in the claim.

The preferred embodiment of the invention 50 has been illustrated in the accompanying drawings, although no restriction is necessarily made to the precise details of construction therein shown, as changes, alterations, and modifications within the scope 55 of the claim may be resorted to when desired.

In the drawings:

Figure 1 is a perspective view of a surf board constructed in accordance with the invention.

60 Fig. 2 is a longitudinal sectional view therethrough.

Fig. 3 is an end view of the board.

Fig. 4 is a vertical transverse section on the line 4-4 of Fig. 1.

65 Like characters of reference denote corresponding parts throughout the several views in the drawing.

Referring now to the drawings in detail the letter A designates a surf board which 70 when constructed in accordance with the invention includes a plurality of floats 5 which are preferably arranged in pairs and with the floats in each pair of floats designated in the drawing by the numerals 6 and 7. 75 The floats 6 and 7, which are of unequal lengths may be constructed from any non-corrosive material and respectively comprise a cylindrical body portion 8 the ends of which are pointed as shown and a longitudinally extending rib 9 formed integral with the float body and serving as a reinforcement therefor.

80 A board 10 rests upon the ribs 9 of the floats 7 and has secured to the sides thereof the ribs 9 upon the floats 6 which are of greater length than the floats 7. Secured to the bottom of the board 10 are transversely extending plates 11 on which are formed spaced ears 12 arranged in pairs 90 with each pair of ears having passed therebetween a rib on one of the floats 7 to which the ears are secured in a suitable manner. One of the plates 11 which is arranged in advance of the floats has connected therewith and with the floats 6 struts 13 by means of which the portions of the floats 6 which extend beyond the floats are braced.

95 The board 10 is cut away upon opposite sides adjacent the rear end thereof to provide recesses 14, so that a person lying upon the board 10 may allow his feet to extend into the water for guiding the board 10. It will be noted with reference to Fig. 1 100 in the drawing that the shape of the recesses 14 are such that the person can freely move his legs for the purpose stated and that the recesses provide the board 10 at its rear end with an extension 15 upon which the feet 110 may be placed when not employed in guiding the board 10. Extending longitudinally

2
of the board 10 between the recesses 14 and the forward end of the board are hand rails 16 which have connected therewith straps 17 by means of which the person employing 5 the device may strap himself thereto if desired, it of course being understood that the hand rails 16 also serve as means by which the board may be carried from place to place and to which a person may hold 10 when launching the board or when coasting on the waves. If desired a pneumatic cushion may be mounted upon the board 10 adjacent its forward end to serve as a chest rest for the person using the board.

15 Depending from the bottom face of the board 10 adjacent the forward end thereof is a frame 18 which is arranged in line with the longitudinal center line of the board 10 and acts as a center board to prevent the 20 overturning of the board when in use. Mounted to turn in a pair of uprights 19 comprising a part of the frame 18 is a propeller shaft 20 to one end of which is fixed a propeller 21. The other end of the 25 shaft 20 has fixed thereto a pinion 22 which is engaged by the teeth on the gear wheel 23 fixed to a shaft 24 mounted to turn in hangers 25 on the board 10.

The shaft 24 has fixed thereto a pair of 30 ratchet wheels 26 and has mounted to turn thereon a pair of arms 27 which are arranged adjacent the wheels 26 and with each arm having fixed thereto a dog 28 which is yieldably held in engagement with the teeth 35 on a ratchet wheel 26 by a spring 29. Each of the arms 27 is pivotally connected with one end of a link 29' the opposite end of

which is pivotally connected with the lower end of the lever 30 which extends above the board 10 through a slot 31 therein and is 40 suitably mounted for swinging movement in boxings 32 on the board.

Through the provision of the levers 30 it will be apparent with reference to the drawing that when the levers are swung by a 45 person lying upon the board 10 the rotation of the shaft 20 may be accomplished for the propulsion by the propeller of the board 10 over the surface of the water, while the occupant of the board may steer the same 50 in any direction desired by letting one of his feet hang within the water upon which the board is supported.

From the foregoing description taken in connection with the accompanying drawing 55 it is apparent that a surf board has been provided which though inexpensive of construction is capable of rendering surf bathing comparatively safe and enjoyable for inexperienced persons.

Having thus described the invention, what is claimed as new, is:—

A device of the class described comprising a board, propelling means carried thereby, 65 transversely extending plates on the bottom of said board, a pair of spaced floats, ears on said plates, ribs on said floats passing between and fixed to said ears, and other floats of greater length than the first-mentioned floats having ribs thereon fixed to 70 said board at opposite sides thereof.

In testimony whereof I affix my signature.

HENRY H. NEWBY.
